UNITED STATES PATENT OFFICE.

FRANCESCO MANARESI, OF FLORENCE, ITALY.

SUGAR-DISPENSING CABINET.

1,206,012.

Specification of Letters Patent. Patented Nov. 28, 1916.

Application filed March 4, 1915. Serial No. 12,091.

To all whom it may concern:

Be it known that I, FRANCESCO MANARESI, a subject of the King of Italy, resident of No. 6 Via Arte della Lana, Florence, in the 5 Kingdom of Italy, have invented new and useful Improvements in Sugar-Dispensing Cabinets, of which the following is a specification.

This invention relates to sugar dispensing 10 cabinets and more particularly to apparatus of the kind in which lumps of sugar need not be stacked in rows or columns but may be introduced pell-mell and in great numbers, suitable provision being made in order 15 that the lumps will be dispensed one by one.

The object of this invention is to provide 20 a sugar dispensing cabinet that will be easier to operate than the apparatus known heretofore; that will not be liable to jam, and will be suitable for use in connection 25 with lumps of sugar of very different sizes.

Other objects are to increase the capacity 30 of such dispensing apparatus and to provide means whereby the extra weight of the increased charge of sugar will not interfere 35 with the smooth operation of the dispensing member.

Various embodiments of the invention are 40 shown by way of example in the annexed drawing in which—

Figure 1 is an outer view, Fig. 2 a vertical section, Fig. 3 a plan of one of such constructional forms. A modified form is represented in Figs. 4 and 5, of which Fig. 4 is 45 a vertical section of the upper part of the apparatus and Fig. 5 a plan of the funnel; Fig. 6 shows another modification of the distributor, partly in elevation and partly in a vertical section of the upper part; Fig. 50 7 is a perspective view of the aforesaid plan Fig. 5 and Figs. 8 and 9 are respectively sections according to $\alpha\alpha$ and $\gamma\gamma$ (Fig. 5).

The apparatus shown in Figs. 1-3 consists 55 of a pedestal as base 1, to which is attached the plate or tray 2 upon which the lumps of sugar fall, the movement imparting gear being placed in the inner part. The latter consists of a couple of conical wheels 3, 4 meshing with each other; the wheel 4 fixed 60 to a toothed disk 5 actuated by a pawl 6 pressed by a spring 7; the pawl is actuated in turn by a lever 8, whose end projects from the pedestal in order to be worked by the finger pressure of the customer. The 65 columns 9, rising from the pedestal, sustain a vessel in the shape of a funnel 10 into

which the sugar lumps are thrown pell-mell; to a cylindrical edge 11 of the said funnel a lid 12 is fixed. Inside a cylindrical box 13, which forms the bottom of the funnel 10 and 60 is bored in the center to leave a passage for the shaft 24 upon which the conical wheel 4 is mounted in the interior part, is placed, and turns with the shaft 24, a member consisting of two cones 15 and 16. The cone 15 65 turns upward, and cone 16 is closely applied to the funneled surface of vessel 10, and is provided with a cylindrical edge 18 on the upper part and by a cylindrical edge 14 on the lower part, the cylindrical edge 18 being 70 immediately below a circular rib 17 which forms the circle of base of the upper cone 15. The sugar lumps piled in the space between the upper part of the funnel 10 and the central conical part in view of the edge 18 can 75 not pass into the funnel 16 except through three, four or more openings 19 made in the said edge. The cylindrical crown 14 is prolonged by an edge 20 somewhat projecting above the lower end of the conical inner 80 surface of the member 16, so as to retain the lumps of sugar passed through the openings 19 and prevents their immediate fall into the cylindrical crown 14. In one part of the conical surface 16 is formed an opening 85 somewhat bigger than the area of the rectangle determined by the longest sides of the sugar lumps. Into this opening a pad 21 forming the end of a spring 22 fixed on the outer part of the funnel 10 can enter when 90 the opening happens to be above it. The pad 21 entering said opening raises the sugar lump above the edge 20, compelling it to fall inside the crown 14, and thence into the box 13, whose bottom is provided with a 95 hole which permits the fall of the sugar lumps into a collecting chute 23, which slopes from the bottom of the box to above the plate 2.

According to the modification shown in 100 Figs. 4 and 5, the funnel 10 in which are placed pell-mell the sugar lumps is secured to a support 25 which, in its turn, is sustained by the columns 9. Through the bottom of the support 25 and through the bottom 105 35 of the lower cylindrical part of the funnel 10, the shaft 24 passes loosely, which can be made to revolve at intervals by a convenient mechanism placed at the foot of the apparatus, as, for example, the one described with reference to Figs. 1 to 3.

The shaft 24 is screw threaded at its end

26 and secured to central body 15 by means of the nuts 27 and 28, the first of which is fixed to the bottom 29, the second to the top 42 of the central body itself. The central body 15 is formed of an upper part in the form of a truncated cone or calotte and of a lower similarly shaped part 30, the two parts being connected along their larger bases, and is provided with a collar 32 which 10 is revolving into the lower cylindrical part of the funnel 10. The conical wall 30 is fitted with some parallelepipedal projections 35 between each pair of which are as many empty spaces 31, also parallelepipedal, having the approximate depth of two lumps of sugar placed side by side. These empty spaces are limited along the sides by the lateral walls 34 of the projections 35, on the bottom by the collar 32 and on the top 20 by the conical wall 30. They open on the front toward the cavity of the funnel 10 and downward toward the conical wall of the funnel itself. In the zone in which the funnel 10 passes from the conical form into the 25 cylindrical form of the bottom there is a circular rib 36 which slightly projects toward the inner part of the conical wall 10 in its lower and narrower zone.

In one point of the funnel 10 an opening 30 37 is made to which is connected the distributing chute 23 going through the support 25. The upper side of the opening 37 is limited by a rib 41 (see Figs. 8 and 9) projecting from the surface of the funnel 10 and somewhat extending beyond the side itself of the opening 37 in two pieces of rib of a height decreasing until zero, in a manner as to form a gradual barrier between the opening and the adjacent parts on one 40 side and the zone of the funnel placed above the said parts on the other side; this upper zone may be made slightly concave at 38 in order to increase the effect of the rib 41.

The apparatus works as follows: The 45 lumps of sugar placed pell-mell into the funnel 10 occupy, in a radial position, two by two in a row (39, 40 Fig. 4) the empty spaces 31, and by the turning of the central body, they are caused to revolve in groups 50 of two, owing to the walls 34 which push them forward, the same leaning against the conical wall of the funnel 10 and being kept with a certain play inside the empty spaces 31 by the rib 36 which limits their descent 55 along the conical wall of the funnel. Whenever a space 31 reaches the top part of the opening 37 the lump of sugar 39 falls through the latter, while the lump 40 is prevented from doing so by the rib 41, so that 60 the fall of only one lump of sugar takes place when one space 31 reaches the opening 37: with the proceeding of the rotation of the central body, in consequence of the lowering of the rib 41, the lumps of sugar 40 65 can descend and assume the position occu-

pied by the lump 39 and a new lump of sugar takes the place of lump 40; this only occurs, when the space 31 has overreached the opening 37. Instead of making the central body rotatable and the outer funnel 70 fixed, one can make the former fixed and cause the latter to revolve.

In order to better control the descent of the sugar lumps into the funnel 10 the upper part 15 of the central body can be 75 done away with making the lower part 30 end with a surface 43 horizontal or slightly inclined toward the outer edge (see Fig. 6). The edge 11 is provided in this case with a hooded cap 44 which forms the shutting 80 of the apparatus and serves to sustain, with its border 45 the vase 46 inside which is placed the whole of the sugar lumps, and a funnel 47 which compels them to fall upon the central part of the surface 43, so that 85 neither the border of the latter nor the funnel 10 has to carry the weight of the whole of the lumps. The part 47 instead of having the shape of a funnel can be cylindrical: it is essential that the vertical distance between the lower border of it and the surface 43 should but little exceed (not more than some millimeters) the dimension of the 90 larger side of the lump. The lumps, obeying the centrifugal force due to the rotation of the surface 43 and eventually to 95 their weight, are displaced toward the border of the surface 43 and fall singly into the space between the funnel 10 and the cone 30: hence they are successively carried to the 100 discharge orifice 37 in the manner described. The rotation of the movable part can be obtained in any obvious manner, either from the top or from the bottom or from the side.

Having now described my invention and 105 how the same is to be carried out, what I claim as my invention, is:

1. Sugar dispensing cabinet comprising in combination a container having a funnel-shaped bottom, a dispensing member fitting in and mounted to rotate within the bottom part of said container, means on the bottom of the container whereby the lumps of sugar engaged by the dispensing member will be discharged one at a time, and means on said dispensing member extending over the said discharging means and coöperating with the walls of the container to support the lumps of sugar contained therein.

2. Sugar dispensing cabinet comprising in combination a container having a funnel-shaped bottom, a hollow dispensing member fitting in and mounted to rotate within the bottom part of said container, said dispensing member having peripheral apertures and 120 being arranged to form, in conjunction with the bottom of the container, an annular race 125 from which the lowermost lumps of sugar are discharged through the apertures of the dispensing member, and means on the bot- 130

tom of the container whereby the lumps of sugar engaged by the dispensing member will be discharged one at a time.

3. Sugar dispensing cabinet comprising
 5 in combination a container having a funnel-shaped bottom, discharging means in the bottom of the container, a hollow dispensing member fitting in and mounted to rotate within the bottom part of said container,
 10 said dispensing member having a smooth top surface extending over the said discharging means and peripheral apertures through which the lumps of sugar are admitted to the discharging means, means on the path of
 15 the lumps of sugar being discharged whereby they will be dispensed one at a time.
 4. Sugar dispensing cabinet comprising
 in combination a container having an upper part or chamber and an enlarged lower part
 20 or chamber having a funnel-shaped bottom, a hollow dispensing member fitting in and mounted to rotate within the lower chamber and arranged so as to leave an annular space between the said dispensing member and the
 25 walls of the container, means on the bottom of the container whereby the lumps of sugar engaged by the dispensing member will be discharged one at a time, the top surface of the dispensing member extending over the
 30 said discharging means and coöperating with the walls of the container to support

the lumps of sugar contained in the lower chamber, and guiding means whereby the lumps of sugar in the upper chamber are caused to bear on the top surface of the dispensing member.

- 35 5. Sugar dispensing cabinet comprising
 in combination a container having a cylindrical upper chamber and an enlarged lower chamber with a funnel-shaped bottom, a hollow dispensing member fitting in and mounted to rotate within the lower chamber and arranged so as to leave an annular space between the said dispensing member and the walls of the container, means on the bottom 40 of the container whereby the lumps of sugar will be discharged one at a time, the dispensing member having peripheral apertures and a smooth and substantially flat top surface extending over the said discharging means,
 45 a substantially cylindrical partition extending beyond the wall of the upper chamber and projecting into the lower chamber to a distance from the top surface of the dispensing member just sufficient to allow for the 50 passage of a lump of sugar.

In testimony whereof I hereunto affix my signature in the presence of two witnesses.

FRANCESCO MANARESI.
